UNITED STATES PATENT OFFICE.

FREDERIC J. HUBBARD, OF CHICAGO, ILLINOIS, ASSIGNOR TO ABNER B. THOMAS AND BARTON SEWELL, OF SAME PLACE.

DENTAL BRACKET.

SPECIFICATION forming part of Letters Patent No. 248,319, dated October 18, 1881.

Application filed January 31, 1881. (No model.)

To all whom it may concern:

Be it known that I, FREDERIC J. HUBBARD, a citizen of the United States, residing at Chicago, in the county of Cook and State of Illinois, have invented a new and useful Dental Bracket, 5 of which the following is a specification.

My invention relates to improvements in dental brackets in which the vertical pivot upon which the entire bracket has its horizontal movement is provided with two parallel arms pivoted one above the other to said pivot, and at their outer ends to a link or clamping-plate provided with a bracket or guide carrying the adjustable horizontally-sliding arm supporting the table of the operator.

The object of my invention is to provide means for adjusting the height of the table or tray, and at the same time maintaining it in a horizontal position, without destroying or interfering with the horizontal movement of the bracket proper. I attain this object by mechanism illustrated in the accompanying drawings, in which—

Figure 1 represents a side elevation of a bracket embodying my invention; Fig. 2, a perspective of the front end of the same, with a part of the plate a' broken away to show bolt e , nut e' , and the segmental arm; Fig. 3, a similar view, taken from the opposite side of the forward end of the bracket; and Fig. 4, a vertical section through the plates a a' , with the bolt shown in full lines and the handle partially broken away.

Similar letters of reference indicate the same parts in the several figures of the drawings.

A represents the pivot upon which the bracket swings horizontally, said pivot having its bearings in a suitable bracket-plate secured to the wall of the room or to the cabinet of the operator.

B B' are parallel bracket-arms, pivoted at their inner ends to the pivot A and at their outer ends between two links or clamping-plates, a a' , so that they may have a vertical movement without destroying their parallelism.

Cast with or otherwise secured to the upper end of the link a' is a bracket or guide, b , provided with a set-screw, b' , and adapted to carry 50 a horizontally-sliding arm, C , supporting on

its outer end, at c , the tray or table of the operator.

Arm B is provided upon its outer end with a stud, d , extending some distance from the links a a' , and forming a bearing for a pivoted segmental rod, D , which passes through a transverse bolt, e , in the links a a' , which bolt is transversely perforated to receive the rod, and is slightly beveled at one end, and at its opposite end screw-threaded to receive a nut or tightening-handle, E .

Loosely secured upon the bolt e is a cone or other shaped clamping washer or plate, e' , provided at its apex with a groove corresponding with the segmental rod, which moves in and is held between the walls of the groove and the opposite wall of the perforation in the bolt, as will now be explained.

The bolt e has a longitudinal movement in its bearings in the links when screwing up or unscrewing the handle E , but is held firmly when the handle is screwed down against the link a , at which time the washer e' comes in contact with plate a , and the segmental rod is thus held fast between the washer and the opposite wall of the perforation in the bolt.

It will be observed that as the outer ends of the bracket-arms B B' move in an arc of a circle, it is necessary that, in order to use a rod clamped in the above manner to maintain the bracket-arms at the desired adjustment, such rod should also move in the arc of a circle, but not necessarily in the same arc; for, by pivoting a segmental rod to the end of one of the bracket-arms it may have a center of its own, though a movable one, as in this case, and thus afford a simple and effectual means for securing a vertical adjustment of the bracket.

Having thus described my invention, what I claim, and desire to secure by Letters Patent, 90 is—

1. The combination, with the pivoted bracket-arms, the links connecting their outer ends, a perforated bolt, and a locking-nut upon said bolt, of a segmental rod pivoted upon the end 95 of one of said arms and passing through and adjustably held in the perforated bolt, substantially as described.

2. The combination, with the bracket-arms B B' and links a a' , of the segmental rod D , 100

perforated screw-threaded bolt *e*, receiving said rod, tightening nut or handle *E*, and a clamping-washer, *e'*, as and for the purpose set forth.

3. The combination, with the horizontally and vertically swinging parallel bracket-arms *B B'* and the horizontally-sliding arm *C*, supporting the table, of the segmental rod *D*, per-

forated bolt *e*, receiving said rod, cone-washer, *e'*, and tightening-handle *E*, substantially as and for the purpose described.

FREDERIC J. HUBBARD.
